US0D1083850S

(12) **United States Design Patent** (10) **Patent No.:** **US D1,083,850 S**
(45) **Date of Patent:** **** Jul. 15, 2025**

(54) **LIGHT-EMITTING ELEMENT MODULE**

(71) Applicant: **HAMAMATSU PHOTONICS K.K.**,
Hamamatsu (JP)

(72) Inventors: **Naoto Sakurai**, Hamamatsu (JP);
Akihiro Oguri, Hamamatsu (JP); **Yuya**
Iwazaki, Hamamatsu (JP)

(73) Assignee: **HAMAMATSU PHOTONICS K.K.**,
Hamamatsu (JP)

(**) Term: **15 Years**

(21) Appl. No.: **29/798,732**

(22) Filed: **Jul. 9, 2021**

(30) **Foreign Application Priority Data**

(57) **CLAIM**

The ornamental design for a light-emitting element module as shown and described.

DESCRIPTION

FIG. 1 is a front view of a light-emitting element module according to the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top and right side perspective view thereof;

FIG. 8 is a rear, bottom and left side perspective view thereof;

FIG. 9 is a sectional view thereof, taken along the line 9-9 in FIG. 3; and,

FIG. 10 is a sectional view thereof, taken along the line 10-10 in FIG. 1.

The broken lines show portions of a light-emitting element module that form no part of the claimed design.

1 Claim, 10 Drawing Sheets
